CLAIM

The ornamental design for a hair accessory organizer, as shown and described.

DESCRIPTION

FIG. 1 shows a top perspective view of a hair accessory organizer, showing my new design.

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof, the bottom plan view being a mirror image thereof;

FIG. 7 is a cross-sectional view taken from 7-7 in FIG. 2 thereof;

FIG. 8 is a cross-sectional view taken from 8-8 in FIG. 4 thereof;

FIG. 9 is a cross-sectional view taken from 9-9 in FIG. 4 thereof;

FIG. 10 is a bottom perspective view thereof; and,

FIG. 11 is a top perspective view shown in its environment. The broken lines in FIG. 11 depict environmental subject matter and form no part of the claimed design.

1 Claim, 9 Drawing Sheets
